UNITED STATES PATENT OFFICE

CHARLES K. PICKLES, OF ST. LOUIS, MISSOURI, ASSIGNOR TO THE AMERICAN ROLL PAPER COMPANY, OF SAME PLACE.

ROLL-PAPER HOLDER AND CUTTER.

SPECIFICATION forming part of Letters Patent No. 445,080, dated January 20, 1891.

Application filed December 24, 1889. Serial No. 334,815. (No model.)

To all whom it may concern:

Be it known that I, CHARLES K. PICKLES, of the city of St. Louis, in the State of Missouri, have invented a certain new and useful Improvement in Roll-Paper Holders and Cutters, of which the following is a full, clear, and exact description, reference being had to the accompanying drawings, forming part of this specification.

10 My invention relates to that class of upright roll-paper holders and cutters in which the weight of the roll of paper is utilized to keep the knife in contact with the paper; and my invention consists in features of novelty 15 hereinafter fully described, and pointed out in the claims.

Figure I is an elevation of my improved holder, showing the roll of paper in dotted lines. Fig. II is a top or plan view in which 20 the roll of paper is removed, but is shown in dotted lines. Fig. III is a detail view illustrating the construction of the roll and knife carrying arrangement. Fig. IV is a modification of the pivot arrangement.

25 Referring to the drawings, 1 represents a base, on the upper surface of which is formed a hollow extension 2, in which fits the lower end of a stem 3. On the stem 3 is a collar 4, that has an internally-flattened portion corresponding to that of the stem 3, and which 30 collar carries a plate 5. From the collar preferably extends a bracket 6 to or about the center of the plate 5, and secured at or near the center of the plate is a vertical spindle 7, over which the roll of paper is placed.

35 The roll of paper is supported on the plate 5 and turns freely thereon as the paper is removed. In the hollow extension 2 also loosely fits a rod 8, to which is secured a knife 11. 40 On the rod 8 is rigidly secured a collar 12, on the upper edge of which is an incline 13. On the collar 4 is a friction-roller 14, that, when a roll of paper is on the holder, rests on the incline 13.

45 The spindle 3 must either fit loosely in the extension 2 or the collar 4 must fit loosely on the stem 3.

The operation is as follows: The parts being in the position shown, the roll of paper 50 is placed on its stand. It will be observed that as the paper is at its largest the knife

will consequently be at its farthest from the center of the roll-carrying plate 5. The roll-carrying plate will then be in the raised position shown and the friction-roller 14 will bear upon the upper end of the incline 13. As the roll of paper decreases in size the weight of the roll of paper will cause the friction-roller to gradually ride down the incline, and thus the knife will be drawn toward the paper.

By making the stem 3 and its collar 4 with flattened sides it will be seen that the paper-stand will remain stationary, while only the knife will move as regards horizontal move- 65 ment.

In the modification shown in Fig. IV, I have shown both the stem 3 and the rod 8 of round form. When made in this form it will be seen that the roll of paper and the knife will be caused to move toward each other.

I do not herein broadly claim the idea of a knife held against a roll of paper by the weight of the paper.

I claim as my invention—

1. The combination of a falling support for a roll of paper, a knife located eccentrically relatively to the center of the roll, having a rotating support, and a connection between the falling support and the rotating support, 80 by which the latter is rotated to cause the knife to move toward the roll by the weight of the roll as the paper is removed, substantially as described.

2. The combination of a suitable base, a spindle for receiving the roll of paper, a falling support for said roll, having a lateral projection, and a knife located eccentrically relatively to the center of the roll, having a rotating support provided with an inclined 90 bearing for said projection, substantially as described.

3. In a roll-paper holder and cutter, the combination of a base, an upright spindle for receiving the roll of paper, a falling support for receiving the roll of paper, a projection on the support, a knife, and a knife-support having an inclined bearing - surface upon which the said projection bears, substantially as and for the purpose set forth.

4. In a roll-paper holder and cutter, the combination of a base, a spindle 7, a roll-sup-

porting disk 5, having a friction-roller 14 and adapted to fall as the size of the roll decreases, a knife, and a knife-supporting rod 8, provided with an incline 13, substantially as and for the purpose set forth.

5. In a roll-paper holder and cutter, the combination of the base 1, stem 3, collar 4, having a projection 14, a disk 5, shaft 8, col-

lar 12, having an incline 13, and a knife secured to the shaft, substantially as and for the purpose set forth.

CHARLES K. PICKLES.

In presence of—
E. S. KNIGHT,
A. M. EBERSOLE.
